UNITED STATES PATENT OFFICE.

GEORGE M. BEARDSLEE AND IRA L. FRENCH, OF CHICAGO, ILLINOIS, ASSIGNEES TO
BEARDSLEE CHANDELIER MANUFACTURING COMPANY, OF CHICAGO, ILLINOIS, A
CORPORATION OF DELAWARE.

46,196.

Specification for Design.

Patented Aug. 4, 1914.

Original application filed April 6, 1914, Serial No. 830,068. Divided and this application filed June 6, 1914.
Serial No. 843,589. Term of patent 7 years.

To all whom it may concern:

Be it known that we, **GEORGE M. BEARDSLEE** and **IRA L. FRENCH**, citizens of the United States, residing at Chicago, in the county of Cook and State of Illinois, have invented a certain new, original, and ornamental Design for Lighting-Fixtures, of which the following is a specification, reference being had to the accompanying drawing, forming part thereof, the design being more particularly shown applied to the part of a lighting-fixture which may be employed either as a ring or band for a ceiling-plate or a body-shell.

In the drawing: Figure 1 is a plan view of our new design, illustrating the same as applied to the ring or band of a ceiling plate. Fig. 2 is a side elevation thereof.

We claim:—

The ornamental design for a lighting fixture, as shown.

GEORGE M. BEARDSLEE.
IRA L. FRENCH.
